[57] CLAIM

The ornamental design for a case for teeth models, as
shown and described.

DESCRIPTION

FIG. 1 is a front elevational view of a case for teeth
models showing my new design;

FIG. 2 is a right side elevational view thereof;

FIG. 3 is a rear elevational view thereof;

FIG. 4 is a bottom plan view thereof;

FIG. 5 is a top plan view thereof;

FIG. 6 is a cross-sectional view thereof, taken on line
6—6 of FIG. 1;

FIG. 7 is a cross-sectional view thereof, taken on line
7—7 of FIG. 5; and,

FIG. 8 is a top perspective view thereof.
